ROBERT G. OLP, OF MANITOWOC, WISCONSIN, ASSIGNOR TO NELSON LUMBER COMPANY, OF TWO RIVERS, WISCONSIN, A CORPORATION OF WISCONSIN.

WASHBOARD.

1,097,765.

Specification of Letters Patent.

Patented May 26, 1914.

Application filed March 20, 1911. Serial No. 615,502.

To all whom it may concern:

Be it known that I, ROBERT G. OLP, a citizen of the United States, residing in Manitowoc, in the county of Manitowoc and State of Wisconsin, have invented new and useful Improvements in Washboards, of which the following is a description, reference being had to the accompanying drawings, which are a part of this specification.

10 This invention has for its object to provide a washboard which will be strong and durable in its construction though adapted to freely permit of the corrugated zinc facing being replaced when worn, to prolong 15 the life of the washboard.

Another object of the invention is to so construct a washboard that it may be quickly and easily assembled, thus facilitating its manufacture and minimizing the cost of 20 production.

Another object of the invention is to so construct a washboard that the rails or side pieces thereof may be completely drained to avoid the accumulation of water therein 25 which would cause the parts to rot.

With the above and other objects in view the invention consists in the washboard herein claimed, its parts and combinations of parts and all equivalents.

30 Referring to the accompanying drawings in which like characters of reference indicate the same parts in the different views: Figure 1 is a front view of a washboard constructed in accordance with this invention, 35 parts being broken away for clearness of illustration; Fig. 2 is a longitudinal sectional view thereof on the plane of line 2-2 of Fig. 1; Fig. 3 is a detail sectional view of the lower end of one of the side 40 rails; Fig. 4 is a transverse sectional detail view of one of the side rails with its connection with the bottom bar; Fig. 5 is a detail view of one end of the bottom bar; Fig. 6 is a transverse sectional view through one 45 of the side rails on the plane of line 6-6 of Fig. 2; and, Fig. 7 is a sectional detail view of the rod connection with the soap holder.

In these drawings 10 indicates a head- 50 piece of ordinary construction which has connected to it the two side rails 11 which are preferably made of sheet metal bent to a C-shape in cross section leaving an open slot between the inturned edges to receive the

edges of the corrugated zinc facing 12 and 55 the edges of the wooden or other backing 13 therefor. A top bar 14, preferably of wood, is rabbeted along its under side to receive the upper edge of the zinc facing 12 and its backing 13 and the ends of said 60 top bar are provided with opposite saw kerfs to receive the inturned edges of the sheet metal side rails 11 in the same manner as with a similar bottom bar 15, shown in Figs. 4 and 5. A sheet metal soap holder 65 16 is secured between the headpiece 10 and the top bar 14 by having its upper edge let into the former and its lower edge bent around the latter, the side edges thereof being confined beneath the upper bend of the 70 side rails 11. A soap retaining rod 17 extends across the soap holder near its lower edge, the ends thereof being passed through openings in the ends of the soap holder and confined therein by means of the side rails 75 11, as shown in Fig. 7. The bottom bar 15 is rabbeted at its upper surface to receive the lower edges of the facing 12 and the backing 13, as shown in Fig. 2, and both the top bar 14 and the bottom bar 15 are 80 held in place by means of screws 18 turned into them after passing through openings in the side rails 11. These screws 18 lock the top bar 14 and the bottom bar 15 against 85 sliding lengthwise of the side rails and also assist the engagement of the side rails with the saw kerfs of the top and bottom bars to prevent a lateral spreading of the side rails. The lower ends of the side rails are provided with wooden blocks 19 which 90 are double rabbeted on their inner faces, as shown in Figs. 2 and 6, to just fill in between the inturned edges of the side rails and prevent such edges engaging material being washed. The wooden blocks 19 are 95 held in place by means of metal strips 20 which have openings through which the screws 18 pass and have inturned lower ends fitting in transverse saw kerfs 21 of the blocks 19, as clearly shown in Fig. 3. The 100 metal strips 20 are sufficiently narrower than the side rails to permit of their lateral adjustment in order to bring their openings into register with the openings of the side rails and thus obviate the necessity for accuracy in positioning the openings. The blocks 19 project beyond the lower ends of 105 the side rails and are rounded to form suit-

able bearing surfaces for the washboard which will not cut or tear the material being washed.

The shape of the side rails is such that 5 they form troughs beneath the edges of the facing 12 and the backing 13 to immediately conduct water away therefrom, and in order to provide an outlet for such troughs below the bottom bar 15, the upper ends of the 10 blocks 19 are cut away at their rear edges, as shown in Figs. 2 and 6 and openings 22 are formed in the lower bends of the side rails opposite such cutaway portions of the blocks to allow the water to pass out of the 15 troughs, thus draining the entire washboard and preventing the accumulation of water at the connections of the parts with the side rails.

By means of this invention the washboard 20 may have its wearing surface renewed when necessary, saving the expense of the purchase of an entirely new washboard. When the wearing surface becomes worn, it is only necessary to remove the screws 18 from the 25 bottom bar 15 when the blocks 19 may be withdrawn by sliding them out of the ends of the side rails and the bottom bar 15 may be likewise withdrawn from the grooves of the side rails together with facing 12. A 30 new zinc corrugated sheet may then be slipped into place by sliding it through the grooves of the side rails and the bottom bar 15 and the blocks 19 are then returned to their proper positions when all will be 35 bound firmly together by replacing the screws 18.

The construction is strong and durable and with all of its advantages it is inexpensive to manufacture.

40 The term "corrugated facing" as herein employed is intended to include any form of rubbing surface suitable for the purpose.

What I claim as new and desire to secure by Letters Patent is:

1. A washboard, comprising side rails of a C-shape in cross section to form longitudinal slots, a corrugated facing slidably fitting in said slots, a bottom bar also slidably fitting in said slots, leg blocks slidably fitting in said slots and abutting the bottom bar at their upper ends and projecting beyond the side rails at their lower ends, said blocks being provided with rabbets to receive the inturned edges of the side rails 50 and guard them from engagement with material operated upon, said blocks being also provided with transverse grooves in their outer faces, locking plates positioned between the blocks and the side rails and extending between the bottom bar and the side rails and provided with flanges to engage the grooves of the blocks, and fastening means passing through the side rails and the locking plates and entering the bottom bar.
2. A washboard, comprising side rails

formed of strips of sheet metal bent to a C-shape in cross section, a headpiece connecting the side rails, a top bar and a bottom bar slidably fitting in the slots formed by the open edges of the side rails, a corrugated facing also fitting in the slots of the side rails between the top and the bottom bars, a sheet metal soap holder having its forwardly-projecting side edges fitting within the slots of the side rails, and a soap-retaining rod passing through openings in said edges of the soap holder and confined in place by the side rails.

3. A washboard, comprising side rails of sheet metal bent to a C-shape in cross section, a corrugated facing slidably fitting in the slots formed by the spaced edges of the side rails, leg blocks slidably fitting in the lower hollow ends of the side rails and filling the same, and means for removably holding the blocks in place, there being a cutaway portion at the upper ends of the blocks and openings in the lower edges of the side rails opposite said cutaway portions of the blocks for draining the side rails and the parts connected with them.

4. A washboard comprising sheet metal channel side rails, a suitable rubbing surface whose edges enter said channels and adapt it to slide therein, a bottom bar whose ends are adapted likewise to slide in the channels, screws passing through the side rails and into the ends of this bottom bar, leg blocks slidably mounted in the lower ends of the side rails and having their upper ends abutting against the said bottom bar, and a plate for fastening each one of these leg blocks in place against said bottom bar, said plate lying between the leg block and the side rail having its lower end clamped to the end of the bottom bar by the same screw that fastens the adjacent end thereof to the side rail.

5. A washboard comprising channel side bars, a rub plate and rub board supported therebetween and attached thereto, a head bar connecting the side bars at their upper ends, a bar connecting the side rails at the upper end of the rub plate, a soap box confined between the said bars, its upper edge being attached to the head bar and its lower edge to the cross bar at the upper end of the rub plate and its side edges entering behind the front flanges of the channel bars, and a soap retaining rod supported in holes in the said side edges of the soap receptacle and having its ends terminate within the channels of the side bars.

6. A wash board comprising channel side bars, a back board and rub plate supported therebetween, a cross bar at the upper edge of the rub board, a head piece attached to the upper ends of the side bars, a sheet metal soap receptacle fitting between the side bars, and the head piece and said cross bar, the

upper edge of the soap receptacle entering a longitudinal slot in the lower face of the head piece, the side edges of the soap receptacle entering the channels in the side bars, and engaging behind the front flanges thereof and the lower edge of the soap receptacle being bent around said cross bar and inclosed between the same and the upper edge of the rub board, and a soap sup-

port extending across the lower part of the 10 soap receptacle.

In testimony whereof, I affix my signature, in presence of two witnesses.

ROBERT G. OLP.
